UNITED STATES PATENT OFFICE.

CHARLES A. DAVIS, OF PASADENA, CALIFORNIA.

DENTAL VULCANIZER.

SPECIFICATION forming part of Letters Patent No. 728,375, dated May 19, 1903.

Application filed September 19, 1902. Serial No. 124,095. (No model.)

To all whom it may concern:

Be it known that I, CHARLES A. DAVIS, a citizen of the United States, residing at Pasadena, in the county of Los Angeles and State 5 of California, have invented certain new and useful Improvements in Dental Vulcanizers; and I do declare the following to be a full, clear, and exact description of the invention, such as will enable others skilled in the art 10 to which it appertains to make and use the same, reference being had to the accompanying drawings, and to the letters of reference marked thereon, which form a part of this specification.

15 This invention relates to new and useful improvements in dental or other vulcanizers; and it consists in the provision of means whereby the pressure of the cover bearing against the vulcanizing-boiler will be equalized upon all parts of its open edge, it being the purpose of this invention to improve upon and simplify this class of inventions by hinging the cover direct to the receptacle in which the boiler is placed and securely clamping 25 the cover to the boiler.

More particularly the invention consists in the provision of a dental vulcanizer in which the boiler is supported in such a manner as to tilt slightly, if necessary, when the cover 30 is swung against the top of the same, whereby the pressure brought to bear upon the cover is equally distributed over the upper edge of the boiler, causing a steam-tight joint as the parts are clamped together.

35 The invention consists, further, in various details of construction and in combinations and arrangements of parts, as will be herein-after fully described, and then specifically defined in the appended claims.

40 My invention is clearly illustrated in the accompanying drawings, which, with the letters of reference marked thereon, form a part of this application, and in which drawings similar letters of reference indicate like parts 45 in the views, in which—

Figure 1 is a side elevation of my improved dental vulcanizer, showing the various parts adjusted in place, parts being broken away to better illustrate the invention and to show 50 the slight tilting movement of the boiler in order to secure an equalization of pressure between the cover and the upper end of the

boiler. Fig. 2 is a perspective view of the upper end of the collar of the casing, showing the shape of the upper edge of said collar, whereby the collar of the boiler is supported at two locations substantially diametrically opposite to allow for a slight tilting movement of the boiler. Fig. 3 is a perspective view of the upper end of the boiler, and 60 Fig. 4 is a side elevation of the upper portion of the boiler-supporting casing, showing the shape of its upper edge.

Reference now being had to the details of the drawings by letter, A designates the casing of the vulcanizer, in which heat is introduced by any suitable means, and B designates a metallic collar or casting forming a part of the casing, the upper end of which collar or casting has two raised pivotal portions B', which are diametrically opposite, and the portion of the upper edge of said collar intermediate said raised portions inclines downward, as at C C.

D designates a vulcanizing-boiler which is 75 preferably of cylindrical shape and provided with a flange E at its upper end, said flange being adapted to rest upon the raised pivotal portion B' at points diametrically opposite each other formed on the upper edge of said 80 flange. When the boiler is mounted as described, it will be observed by an examination of Fig. 1 of the drawings that said boiler will be allowed to tilt slightly in opposite directions. In order to get this tilting effect, 85 if preferred, the upper marginal edge of the collar of the casing may be flat and the under edge of the flange of the boiler may be formed with pivotal bearings, intermediate 90 which bearings the under surface of the flange may be inclined, the essential feature of the invention being to produce means whereby a boiler is adapted to tilt when the cover is forced against the same to produce a steam-tight joint. Immediately above the 95 flange of the vulcanizing-boiler is a shoulder E', and F designates a cover to the boiler, which has an annular recess F', (shown clearly in Fig. 2 of the drawings,) in which a gasket is placed, which recess is adapted to receive the upper contracted annular portion 100 e of the boiler. On the upper surface of the cover is a ribbed extension H integral therewith, one end of which is mounted on a piv-

otal pin K', carried by an integral projection K, forming part of the casing. Said ribbed portion of the collar is recessed, as at L, Fig. 2 of the drawings, and is provided with an 5 integral handle M, whereby the cover may be easily raised and lowered. At a location diametrically opposite the integral projection K, forming a part of the casing, is a recess N, through the walls of which the pin 10 N' passes, forming a pivot on which the lower end of the threaded screw O is mounted. Said screw carries an adjusting-nut O' on its threaded portion, whereby as the cover is closed over the top of the vulcanizing-boiler 15 15, said screw may be swung into a vertical position into the recess L in the ribbed portion of the cover, and by screwing down the nut O' by means of a hand-wheel Q said nut will bear against the upper ribbed portion of the 20 cover, and it will be observed that the pressure exerted upon the gasket interposed between the boiler and cover will be equalized, thereby causing a steam-tight joint. The cover of the vulcanizer is provided with the 25 usual thermometer R and with the safety-valve S and blow-off pipe T of the usual construction, and suitable apertures are formed in the circumference of the collar of the casing, whereby exit means is provided for the 30 heat to escape from the interior thereof.

From the foregoing it will be observed that by the provision of a dental vulcanizer embodying the principle of my invention apparatus of this kind is greatly simplified, and 35 the cover to the vulcanizing-boiler is hinged direct to the collar of the casing, thus dispensing with the usual separate cross-bar connection above the cover of the vulcanizer.

Having thus fully described my invention, 40 what I claim as new, and desire to secure by Letters Patent, is—

1. A dental vulcanizer in which the vulcanizing-boiler is adapted to tilt slightly as pressure is applied to a cover bearing against 45 the boiler, whereby the pressure of the cover against the boiler is equalized, thereby making a steam-tight joint, as set forth.

2. A dental vulcanizer comprising a casing, a boiler mounted therein, a cover hinged to 50 the casing and adapted to bear against said boiler, said boiler being adapted to tilt slightly as the cover is forced against the boiler, whereby the pressure of the cover against the rim of the boiler is equalized, as set forth.

55 3. A dental vulcanizer comprising a casing, a cover hinged thereto, a boiler contained within said casing and supported thereby, and means for applying pressure to the cover at a point opposite its pivotal portion, where- 60 by as the cover is forced against the boiler, the latter is adapted to tilt slightly, thus causing an equalization of pressure upon the upper end of the boiler, as set forth.

4. A dental vulcanizer comprising a casing,

a cover hinged thereto, a locking-screw piv- 65 oted to the casing, a tightening-nut mounted on said screw and adapted to bear against the cover, whereby the latter may be forced down against the top of the boiler, which is adapted to tilt slightly, thus enabling the pressure 70 to be equalized upon the upper end of the boiler, and thereby making a steam-tight joint, as set forth.

5. A dental vulcanizer comprising a casing, a boiler contained therein and supported 75 thereon, a cover pivotally connected to said casing, a screw pivoted at a location diametrically opposite the pivotal part of the cover and adapted to swing into a recess in the cover, and a tightening-nut mounted on said screw 80 and adapted to bear against the cover, the contact-surfaces between the casing and the boiler being so constructed that the boiler is adapted to tilt slightly as the cover is forced against the boiler, thereby equalizing the 85 pressure upon the same, as set forth.

6. A dental vulcanizer comprising a casing, a boiler contained within said casing and adapted to rest at two locations diametrically opposite on the upper edge of said casing, a 90 cover pivoted to the casing and means for forcing the cover against the boiler, which is so constructed as to tilt slightly, whereby the pressure upon the same is equalized so as to make a steam-tight joint, as set forth. 95

7. A dental vulcanizer comprising a casing, a boiler contained therein and adapted to rest upon portions of the edge of the casing forming pivotal points at locations diametrically opposite, a cover hinged to the casing, and a 100 tightening-screw for forcing the cover against the boiler, whereby the boiler is allowed to tilt slightly to equalize the pressure of the cover against the end thereof, as set forth.

8. A dental vulcanizer comprising a casing, 105 the upper end of which is provided with two pivotal points at locations diametrically opposite, a boiler contained within the casing and having a flange or collar adapted to rest upon said pivotal points, a cover pivoted to 110 the casing, a screw also pivoted to the casing, and a tightening-nut carried on said screw and adapted to bear against the cover to force the same against the boiler, whereby the pressure on the upper end of the latter is equal- 115 ized, as set forth.

9. A dental vulcanizer having a casing, a boiler-supporting surface, upon the upper marginal edge of which are formed pivotal points at locations diametrically opposite, as 120 set forth.

In testimony whereof I affix my signature in presence of two witnesses.
